(57) **CLAIM**

The ornamental design for an injection molding machine as shown and described.

DESCRIPTION

FIG. 1 is a front view of an injection molding machine in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is an enlarged view of portion 10 of FIG. 8; and, FIG. 11 is an enlarged view of portion 11 of FIG. 9.

The broken lines shown in the drawings represent portions of the injection molding machine that form no part of the claimed design. The dashed-dot-dashed lines indicate a boundary between the claimed portions and the unclaimed portions of the design. The dashed-dot-dashed lines with a reference number in FIGS. 8 and 9 indicate enlarged portions.
